UNITED STATES PATENT OFFICE.

GIDEON C. BATTEN, OF CINCINNATI, OHIO.

SHAKER SCREEN MECHANISM.

1,177,676.

Specification of Letters Patent.

Patented Apr. 4, 1916.

Application filed September 15, 1915. Serial No. 50,896.

To all whom it may concern:

Be it known that I, GIDEON C. BATTEN, a citizen of the United States, residing at Cincinnati, in the county of Hamilton and State 5 of Ohio, have invented certain new and useful Improvements in Shaker Screen Mechanism, of which the following is a specification.

My invention relates to improvements in 10 screening apparatus.

One of its objects is to provide an improved screen or riddle for the use of molders and the like.

Another object is to provide improved 15 means to insure the breaking up and passage through the riddle of any lumps of clay or loam which may occur in or be added to the charge.

Another object is to provide a riddle having 20 increased capacity and able to retain pieces of metal while breaking up and screening lumps of clay or loam.

Another object is to provide a riddle for 25 molders' purposes having increased wearing qualities.

My invention also comprises certain details of form combination and arrangement, all of which will be fully set forth in the description of the accompanying drawings in 30 which:

Figure 1 is a perspective view of one type of power operated screen or shaker with my improvements attached thereto. Fig. 2 is a vertical sectional detail through the riddle. 35 Fig. 3 is a perspective view of the screen detached. Fig. 4 is a perspective view of the charge vibrating and lump breaking member detached.

Screens or riddles as employed by molders 40 have several functions to perform. They are employed to separate stones, lumps, and pieces of metal from the sand or loam, to mix different grades of sand together and to mix certain clays and loams with the sand, 45 to secure the desired texture of material for molding purposes. The stones and pieces of metal tend to quickly wear out the perforated bottom of the screen. The clays and loams usually consist largely of more or less 50 dense, tenacious lumps of different sizes which resist passage through the screen whether in the dry or damp state. To reject these lumps of clay together with the stones

and pieces of metal would result in rejecting the most expensive and desirable of the substances entering into the composition of the molding sand, and my improved apparatus is designed to separate the stones and pieces of metal, to avoid excessive wear on the screen and at the same time to break up the 60 lumps of clay or loam so as to pass the substance thereof through the screen and intimately mix it with the sand.

The accompanying drawings represent the preferred embodiment of my invention as 65 applied to one type of power driven riddles.

As illustrated A represents a tripod upon which is mounted a pneumatic cylinder B and its plunger C. Directly attached to, so as to reciprocate with the plunger C is a 70 split ring or band D having a clamp bolt 2 to unite its ends.

E represents a metal band or frame having its lower edge 3 flanged inwardly, or if desired inwardly projecting lugs may be employed in place of a continuous flange. I preferably but not necessarily employ a perforated sheet metal screen F instead of a woven wire screen and this screen F rests at its periphery upon the flange 3. The band 80 E is firmly but detachably clamped in place within the split ring D. This enables either the band E or screen F to be readily discarded and replaced when worn. If desired, however, the split ring D may be omitted 85 and the band E attached directly to the plunger C. The band D is pivotally supported relative to the tripod by means of links f.

Above the screen F and normally resting 90 thereon is a perforated metal plate H, which has an upwardly projecting stem or post 6 to which is loosely pivotally attached one end of a link 7 preferably upon a horizontal axis. At its opposite end the link 7 is loosely 95 pivotally attached upon a horizontal axis to a link or bar 8 which in turn is pivotally attached upon a vertical axis to a post or bracket 9 which is carried rigidly by the frame 10 at the top of the tripod which carries the pneumatic cylinder B. Thus as the screen comprising the parts E and F is reciprocated rapidly backward and forward by the plunger C, the plate H being attached by the link 7 and bar 8 to the stationary 100 tripod and being of less diameter than the

band E is free to move vertically in different directions horizontally within the confines of the band E. When the screen is in motion the plate H moves in various directions across the interior of the riddle striking against the inner face of the band E and rebounding therefrom. When sand clay loam or like material to be screened is fed into the screen the plate H when properly proportioned and of approximately the proper weight will work up into and partially ride upon the charge assuming a horizontal position or one slightly inclined to the horizontal and will travel backward and forward through the upper strata of the charge catching the lumps at its edges and through its perforations cutting up and disintegrating any lumps of clay or loam, and as the charge passes out through the bottom of the screen the plate H will follow the charge downwardly to keep in contact with the lumps, and will rise again when fresh material is fed in. In practice the plate H is of sheet or cast metal with perforations of sufficient diameter to receive and pass the unbroken lumps, and from one fourth to one half of an inch in thickness, depending upon the weight desired therein. The perforations of the screen F are preferably tapered from the inside outwardly or downwardly so that any particle having once passed the narrow neck of the perforation may readily escape and not clog the screen. Stones or pieces of metal will readily slide over the comparatively smooth inner face of the screen F without material injury thereto, and in the absence of a charge the plate H will ride upon the inner face of the screen with but little wear. The action of the plate H in addition to disintegrating the lumps, materially assists in rapidly passing the charge through the screen and keeping it uniformly spread over the face thereof. The plate H should be properly proportioned as to weight; it should be heavy enough to disintegrate the lumps and cut its way through the charge, and should not be so heavy as to injure the parts E and F, or to fail to ride up into the charge.

50 My improved apparatus may be operated by hand or employed in connection with any of the various riddle power operating devices.

The mechanism herein illustrated and described is capable of considerable modification without departing from the principle of my invention.

Having described my invention, what I claim is:

60 1. A shaker mechanism comprising a receptacle for the material to be screened having a perforated bottom and supported in position to have a shaking movement imparted thereto to work the finer portion of the charge through the perforations of its

bottom, and a disintegrator member located loosely in said receptacle and separately controlled to cause said disintegrator member to strike the walls of said receptacle and move in different directions within and relative to said receptacle when a shaking movement is imparted to said receptacle. 70

2. A shaker mechanism comprising a receptacle for the material to be screened having a perforated sheet metal bottom and supported in position to be reciprocated to work the finer portion of the charge through the perforations of its bottom, a disintegrator member of less diameter than said receptacle located loosely in said receptacle and jointly attached to a stationary support outside of said receptacle to cause said disintegrator member to strike the walls of said receptacle and to rebound therefrom and move in different directions within and relative to said receptacle when said receptacle is reciprocated. 80

3. A shaker mechanism comprising a receptacle for the material to be screened having a perforated bottom and supported in position to be reciprocated to work the finer portion of its charge through the perforations of the bottom, a disintegrator member of less diameter than said receptacle located loosely in said receptacle and adapted to ride in and cut through the charge in said receptacle, said disintegrator member by striking the walls of said receptacle at different points when a shaking movement is imparted to the receptacle being energized 100 to cross-cut the charge in different directions. 95

4. A shaker mechanism comprising a receptacle for the material to be screened having a perforated bottom and supported in position to be moved to work the finer portion of its charge through the perforation of its bottom and a disintegrator member of less diameter than said receptacle adapted by striking the walls of said receptacle to ride in and cross-cut the charge above the bottom of said receptacle in different directions, when said receptacle is reciprocated. 110

5. A shaker mechanism comprising a receptacle for the material to be screened having a perforated sheet metal bottom and supported in position to be reciprocated to work the finer portion of the charge through the perforations of its bottom, means to reciprocate said receptacle, a disintegrator member of less diameter than the receptacle loosely mounted in said receptacle and separately controlled to cause it by striking the walls of said receptacle to ride in and cross-cut the charge when said receptacle is reciprocated. 120

6. A shaker mechanism comprising a cylindrical receptacle for the material to be screened having a perforated bottom and supported in position to have a shaking 130

movement imparted thereto to work the finer portion of the charge through the perforations of its bottom, and a disintegrator of less diameter than the receptacle movably mounted in said receptacle and separately controlled to cause it to strike the walls of said receptacle at different points and to move in different directions through the

charge due to the shaking movement of said receptacle.

10

In testimony whereof I have affixed my signature in the presence of two witnesses.

GIDEON C. BATTEN.

Copies of this patent may be obtained for five cents each, by addressing the "Commissioner of Patents, Washington, D. C."

It is hereby certified that in Letters Patent No. 1,177,676, granted April 4, 1916, upon the application of Gideon C. Batten, of Cincinnati, Ohio, for an improvement in "Shaker Screen Mechanism," an error appears in the printed specification requiring correction as follows: Page 2, line 1, after the word "vertically" insert the word *and*; and that the said Letters Patent should be read with this correction therein that the same may conform to the record of the case in the Patent Office.

Signed and sealed this 30th day of May, A. D., 1916.

[SEAL.]

J. T. NEWTON,

Acting Commissioner of Patents.
